CLAIM

The ornamental design for a cigarette lighter, substantially as shown and described.

DESCRIPTION

FIG. 1 is a side elevational view of a cigarette lighter showing my new design, the opposite side being substantially a mirror image thereof;

FIG. 2 is a front elevational view thereof;

FIG. 3 is a rear elevational view thereof;

FIG. 4 is a top plan view thereof; and

FIG. 5 is a bottom plan view thereof.
